UNITED STATES PATENT OFFICE.

ALVIN G. SHERMAN, OF DETROIT, MICHIGAN, ASSIGNOR TO DETROIT VAPOR STOVE COMPANY, OF DETROIT, MICHIGAN, A CORPORATION OF MICHIGAN.

STOVE-BASE CONSTRUCTION.

Application filed July 15, 1922. Serial No. 575,318.

To all whom it may concern:

Be it known that I, ALVIN G. SHERMAN, a citizen of the United States, residing at Detroit, in the county of Wayne and State of Michigan, have invented certain new and useful Improvements in Stove-Base Constructions, of which the following is a specification.

This invention relates to gas and vapor stove construction and has for its object a construction of the base frame and associated parts so that the bolt heads and other fastening devices are completely concealed from sight when the stove is under ordinary observation. Further, a strong and stiff base construction is afforded which affords a stable and rigid stove.

In the drawings,—

Fig. 1 is a front perspective of the stove.
20 Fig. 2 is a plan view of the base construction.

Fig. 3 is a section on the line 3—3 of Fig. 2.

Fig. 4 is a section on the line 4—4 of 25 Fig. 2.

Fig. 5 is a section on the line 5—5 of Fig. 1.

Fig. 6 is a section on the line 6—6 of 30 Fig. 1.

The various parts that go to make up the stove are plainly evident from the plan view of Fig. 1 and it will not be necessary to detail them. It will be noted, however, from an observation of this view that not a single 35 fastening device is seen on the stove. These are all concealed by the various features of construction that are embodied in several applications that are co-pending.

This application is limited to the base 40 frame and leg construction and associated parts of the stove which form a joint therewith completely eliminating any exposed bolts and nuts and other fastening devices.

The base frame is an angle bar *a* which 45 has its horizontal web recessed as at *b* to permit the bar to be bent around the corners at three corners and at the fourth corner, the angle bracket *c* serves to connect the ends of the angle frame together. This single bar of 50 angle section gives a very strong, rigid base frame.

The legs *d* are of angle section and taper 55 toward the bottom. The enlarged portion at the top has a horizontal web *e*. The walls of the stove, back, side and front, are all turned

in under the horizontal web of the angle iron as shown in Figs. 3, 4, 5 and 6. The bolts and nuts *f* serve to clamp the turned in flanges to the under side of the horizontal web of the angle bar. Where the stove legs 60 join the frame, the turned in flange rests between the bottom of the angle bar web and top web *e* of the stove leg. The stove bolt and nut here both fasten the wall and the leg to the angle bar.

The warming chamber bottom *g* and the side and back walls of the stove are of sheet metal and are easily turned under. The oven front frame *h* is a pressed steel frame, although it could be a casting and has a section which is roughly a channel section. The bottom of this bar passes under the web of the angle bar as is plainly shown in Fig. 5 and is securely bolted thereto by bolts and nuts *f*.

What I claim is:

1. In stove construction, the combination of a base frame made up of bar members, a stove wall, having a flange turned under said bar members, and means for connecting 65 said flange to said bar members in concealed relation.

2. In stove construction, the combination of a base frame comprising bar members, a stove wall having a flange turned under the 70 bar members, a stove leg having a top web, and concealed fastening devices arranged to clamp the base frame, the flange of the wall and the top web of the stove wall together.

3. In stove construction, the combination 75 of a base frame comprising a bar of angle section, a stove wall having a turned under flange engaging under the horizontal web of said bar, a stove leg provided with a top web and concealed fastening devices for fastening the angle bar, the turned in flange and the top web of the leg together with the flange pinched between the angle bar and the leg.

4. In stove construction, the combination 80 of a base frame, having an angle bar section, a stove wall having a flange turned in at right angles and fitting under the horizontal web of the angle bar, a stove leg provided with a top web, and bolts and nuts passing through the horizontal web of the angle bar, the flange of the wall and the top web of the leg for fastening these members together and pinching the flange between the angle 85 bar and the leg.

5. In stove construction, the combination of an angle section base frame, a channel-like front frame having its lower edge turned in and secured to the under side of the horizontal web of the angle section base frame, and concealed fastening devices for removably securing said turned in under edge of the front frame to the web of said base frame.

6. In stove construction, the combination of an angle section base frame, a stove wall having its lower edge turned under the horizontal web of the base frame and concealed bolts and nuts for securing the said turned in edge removably to said horizontal web of the base frame. 10 15

In testimony whereof I affix my signature.
ALVIN G. SHERMAN.
